(57) **CLAIM**

The ornamental design for a hood ornament, as shown and described.

DESCRIPTION

FIG. 1 is a top perspective view of a hood ornament according to our new design;

FIG. 2 is a bottom perspective view of the hood ornament of FIG. 1;

FIG. 3 is a top plan view of the hood ornament of FIG. 1;

FIG. 4 is a bottom plan view of the hood ornament of FIG. 1;

FIG. 5 is a front elevational view of the hood ornament of FIG. 1;

FIG. 6 is a right side elevational view of the hood ornament of FIG. 1, the left side elevational view thereof taken from the side opposite of FIG. 6 being mirror symmetrical; and, FIG. 7 is a rear elevational view of the hood ornament of FIG. 1.

The broken lines depicted in FIGS. 2, 4, and 6 are boundary lines that define the bounds of the claimed design and form no part of the claimed design.
